UNITED STATES PATENT OFFICE.

WILLIAM S. LUCKETT, OF EAST ORANGE, NEW JERSEY, ASSIGNOR TO INTERNATIONAL CIGAR MACHINERY COMPANY, OF NEW YORK, N. Y., A CORPORATION OF NEW JERSEY.

CIGAR WRAPPING MECHANISM.

1,075,216.

Specification of Letters Patent.

Patented Oct. 7, 1913.

Application filed May 31, 1908. Serial No. 318,610.

To all whom it may concern:

Be it known that I, WILLIAM S. LUCKETT, a citizen of the United States, residing at East Orange, county of Essex, and State of New Jersey, have invented certain new and useful Improvements in Cigar-Wrapping Mechanisms, fully described and represented in the following specification and the accompanying drawings, forming a part of the same.

This invention relates to certain improvements in machines for wrapping cigars.

In cigar machines in which the wrapper is automatically presented to the bunch in the wrapping mechanism, it has been found desirable to control the wrapper as it passes from the wrapper presenting means to the wrapping mechanism by a guide over which the wrapper passes, this guide being located between the wrapper presenting means and the wrapping mechanism. The function of this wrapper controlling device is to so direct the wrapper to the rolling bunch that it may be smoothly wrapped thereon, and to also, to a certain extent, at least, effect the proper delivery of the wrapper from the presenting means, particularly in that class of machines in which the wrapper presenting means embodies a suction carrier. Some wrapping machines employ a device such as a needle to hold the tuck end of the wrapper on the rotating bunch while the first wrap is made, and in one of the prior machines, this needle was so operated as to not only hold the tuck end of the wrapper on the bunch, but to positively engage the wrapper while on the wrapper carrier and transfer the tuck end thereof from the carrier to the bunch, after which it held this end of the wrapper on the bunch until the first wrap was made.

One of the objects of this invention has in view to provide an improved cigar machine which shall include a wrapper controlling device operating on the wrapper between the wrapper presenting device and the wrapping mechanism, this device being positively moved lengthwise of the wrapping mechanism during the wrapping operation.

A further object of the invention is to provide cigar machines which shall embody improved means for operating the wrapper transferring device.

With these and other objects not specifically referred to in view, the invention con-

sists in certain constructions and in certain parts, improvements and combinations as will be hereinafter fully described and then specifically pointed out.

Referring to the accompanying drawings—Figure 1 is a plan view of so much of a cigar machine as is necessary to an understanding of the invention. Fig. 2 is a side elevation of the construction shown in Fig. 1. Fig. 3 is a section on the line 3—3 of Fig. 1. Fig. 4 is a detail elevation, partly in section, of the devices for operating the wrapper controlling means. Fig. 5 is a detail side elevation of the devices for operating the wrapper transferring means. Fig. 6 is an end elevation of the construction shown in Fig. 5.

The wrapping mechanism with which the improved controlling device hereinafter to be described is employed may be of any suitable construction. In the construction illustrated, the wrapping mechanism is supported between a pair of side frames 1, these frames being connected by cross webs 2, 3 and 4. The wrapping devices proper are mounted so as to depend from this frame and the frame may, if desired, be constructed and mounted in the machine so that it may be swung up to permit access to the wrapping devices. As shown, the side frames 1 are provided with bearings 5 in which pintles may be located.

The wrapping is effected, in the particular construction shown, by means of rolls 6, 7 and 8, the rolls 6 being provided with a gear 9, the roll 7 with a gear 10 and the roll 8 with a gear 12. The gear 10 is in mesh with an intermediate 13 and the gear 12 with an intermediate 14, these intermediates being both in mesh with the gear 9. The roll 7 is mounted in a side frame 15 and the roll 8 in a side frame 16, these frames being pivoted so that the rolls 7, 8 may be opened to receive and discharge the bunch by swinging the frames. This is effected by providing the frame 15 with an arm 17 and the frame 16 with an arm 18. The arm 18 is connected by a link 19 with a lever 20 pivoted at 21 in the frame, and the arm 17 is connected by a link 22 to this same lever 20. This lever 20 is provided with a stud which engages a cam groove 23 in a cam drum 24, this cam drum being mounted on a shaft 25 which is the main cam shaft of the wrapping machine. This shaft 25 may be driven

in any suitable manner, as, for instance, by a gear 26, to which motion is communicated from any suitable gear in the machine.

The best constructions will embody a 5 wrapper presenting device. That shown includes a suction plate 27 overlying a suction chamber 28, the plate forming a carrier by which the wrapper is delivered to the wrapping mechanism. A relative movement 10 will be set up, during the wrapping operation, between the wrapper carrier and the wrapping mechanism to effect the proper delivery of the wrapper. While this relative movement may be varied in its character, it will consist in part of a relative traversing movement such as is generally described in the patent to Tyberg, No. 654,203, this movement effecting the proper delivery 15 of the wrapper lengthwise of the bunch during the wrapping operation. The mechanical agencies by which this movement is accomplished are not material to the present invention and are, therefore, not described, as any suitable means may be employed 20 for this purpose. It may be remarked, however, that a suitable mechanism is disclosed in an application of Oluf Tyberg, Ser. No. 264,568, filed June 10, 1905.

The construction of the wrapper controlling device employed may be varied 30 widely. In the particular construction illustrated, this controlling device consists of a plate 29, this plate being provided with rearwardly projecting arms 30 by which the 35 plate is pivoted to depending arms 31, these arms being connected by a cross-web 32 and being carried on a hub 33 loosely mounted on a rod 34 suitably supported in one of the side frames 1. In the particular construction 40 illustrated while the wrapper is being delivered from the suction carrier to the rolls, the plate stands well across the opening between the rolls 7 and 8, so that the plate is moved into and out of operative position to 45 permit the delivery of the bunch to and its discharge from the wrapping mechanism. This movement of the plate is effected by swinging the arms 31 by a mechanism which will be hereinafter described.

50 During the delivery of the wrapper, the controlling device or plate 29 is given a movement lengthwise of the wrapping mechanism, so that it may at all times preserve a proper relation with respect to the 55 wrapper. While the means employed for producing this lengthwise movement may be varied and will be varied according to the type of controlling device employed, in the particular construction illustrated, the hub 60 33 is provided with a slot which is engaged by a roll 35 mounted on the end of a swinging lever 36, this lever being pivoted at 37 to a standard 38 rising from one of the side frames 1. This lever 36 is provided with 65 an outward projection or wing in which is

formed a slot 39, this slot being engaged by a roll 40 on a cam lever 41, this lever being pivoted on a stud 42 secured to one of the side frames. The lower end of this lever carries a roll 43 which engages with a cam 70 groove 44 in the cam drum 24 before referred to. As the cam drum 24 rotates, therefore, the hub 33 will be slid lengthwise on its supporting rod 34, thus at all times during the wrapping operation 75 properly positioning the controlling plate with respect to the wrapper. The movement of the plate into and out of position is effected by providing the hub with a short arm 45 which has a roll 46 thereon, this roll being located in a cam slot 47 in a plate 48 secured to the side frame. This slot is provided with a sharp incline 49 which is engaged by the roll 46 just as the hub begins its longitudinal movement, so that the 80 hub is rocked, thus carrying the arms 31 and the controlling plate forward so as to bring the plate into proper position with respect to the wrapper. It has been heretofore stated that the plate is carried by arms 85 30 which are pivoted to the arms 31, and in order to control the position of the plate as it moves inward, one of the arms has a rearward extension 50, this being provided with a cam roller 51 which bears against a swinging cam 52, the roll 51 being held up against this cam by means of a spring 53 fast to a pin 54 on the hub 33. The cam 52 is carried by an arm 55 which is pivoted to the hub 33, this arm being provided with a roll 100 56 which bears on the underside of the plate 48, this plate having a bevel cam face 57 thereon of the configuration necessary to produce a substantially parallel inward movement of the arms 30 as they are carried 105 inward and outward by the movements of the arms 31. The purpose of this part of the construction is to cause the edge of the plate 29 as the arms 31 swing to be maintained always at substantially the same distance from the face 27 of the suction wrapper carrier.

The transferring device for the wrapper when the same is employed may be variously constructed. As shown, it consists of 115 a flexible needle 58, this needle being caused by a suitable mechanism to transfer the wrapper to the bunch and hold it thereon while the first wrap is made. In the particular construction shown, the needle engages the wrapper while it is on the wrapper carrier or presenting device, this being effected, in the construction shown, by providing the carrier with a groove 59 which the needle enters. The mechanism for giving the needle its movement may be considerably varied. As illustrated, it is mounted in a carrier 60 which consists of a short arm 120 this arm being mounted on a short shaft 61 carried in a swinging arm 62. The upper 125

end of this arm 62 is formed with a yoke 63, this yoke being pivoted by a pin 64 to one of the side frames 1. The lever 62 has a connecting rod 65 pivoted to it, this rod being pivoted at its other end to a lever 66 which is in turn pivoted to one of the side frames. This lever 66 carries a roll 67 which engages a cam groove 68 in the drum 24 before referred to. The shaft 61 is provided with a torsion spring 69 which normally holds the carrier 60 and the needle 58 up against a swinging cam 70 pivoted at 71 to one of the side frames, the carrier 60 having a roll 72 which bears against the operating face of this cam. The cam 70 is provided with an inclined operating face 73 and with a straight face 74. As the arm 62 starts to move inward, the inclined face 73 operating against the roll 72, throws the carrier 60 down against the force of the torsion spring 69 and properly positions the needle 58, so that it may enter the slot 59 in the wrapper presenting device. The further movement of the arm 62 causes the needle to enter the slot 59, the roll 73 at this time running on the straight face 74 of the cam 70. At the time when the needle has fully engaged the wrapper, the roll 73 rides off the cam and permits the torsion spring to operate, this spring causing the needle to take the tuck end of the wrapper from the wrapper support to the bunch in the wrapping rolls. The needle remains in position until the first wrap of the wrapper around the bunch is completed, the wrapper being drawn over the edge of the plate 29 which thus controls its proper delivery to the bunch. After the wrapper has been given its first wrap around the bunch, the needle is withdrawn by a reverse movement of the arm 62. The cam 70 is held in its operative position by means of a spring 75 connected to the cam at 76 and to a pin 77 on one of the side frames, this spring permitting the cam to swing back as the arm 62 is making its reverse movement, thus allowing the roll 72 to get out from behind the cam.

Changes and variations may be made in the construction by which the invention is carried into effect. The invention is not, therefore, to be limited to the specific construction herein shown and described.

What is claimed is:—

1. The combination with a wrapping mechanism, of a wrapper presenting device, a wrapper controlling device operating on the wrapper between the presenting device and the wrapping mechanism, and means for moving the controlling device lengthwise of the wrapping mechanism during the wrapping operation.

2. The combination with a wrapping mechanism, of a suction wrapper presenting device, a wrapper controlling device op-

erating on the wrapper between the presenting device and the wrapping mechanism, and means for moving the controlling device lengthwise of the wrapping mechanism during the wrapping operation.

3. The combination with a wrapping mechanism, of a wrapper presenting device, a wrapper controlling plate operating on the wrapper between the presenting device and the wrapping mechanism, and means for positively moving the plate lengthwise of the wrapping mechanism during the wrapping operation.

4. The combination with a wrapping mechanism, of a suction wrapper presenting device, a wrapper controlling plate operating on the wrapper between the presenting device and the wrapping mechanism, and means for positively moving the plate lengthwise of the wrapping mechanism during the wrapping operation.

5. The combination with a wrapping mechanism, of a wrapper presenting device, a wrapper controller operating on the wrapper between the presenting device and the wrapping mechanism, means for moving the controller into and out of operative position, and means for positively moving it lengthwise of the wrapping mechanism during the wrapping operation.

6. The combination with a wrapping mechanism, of a suction wrapper presenting device, a wrapper controller operating on the wrapper between the presenting device and the wrapping mechanism, means for moving the controller into and out of operative position, and means for positively moving it lengthwise of the wrapping mechanism during the wrapping operation.

7. The combination with a wrapping mechanism, of a wrapper presenting device, a wrapper controller plate operating on the wrapper between the presenting device and the wrapping mechanism, means for moving the controller into and out of operative position, and means for positively moving it lengthwise of the wrapping mechanism during the wrapping operation.

8. The combination with a wrapping mechanism, of a suction wrapper presenting device, a wrapper controller plate operating on the wrapper between the presenting device and the wrapping mechanism, means for moving the controller into and out of operative position, and means for positively moving it lengthwise of the wrapping mechanism during the wrapping operation.

9. The combination with a wrapping mechanism, of a suction wrapper presenting device, a support, a wrapper controller plate pivoted on the support, means for moving the support to carry the plate toward and away from the wrapping mechanism, means for moving the plate with respect to the support to position it, and means for giv-

ing the support an endwise movement during the wrapping operation to move the plate lengthwise of the wrapping mechanism.

- 5 10. The combination with a wrapping mechanism, of means for presenting a wrapper thereto, means for transferring the tuck end of the wrapper to the bunch in the wrapping mechanism and hold it against the
- 10 bunch, a wrapper controlling device operating on the wrapper between the presenting device and the wrapping mechanism, and means for moving the controlling device lengthwise of the wrapping mechanism during the wrapping operation.
- 15 11. The combination with a wrapping mechanism, of a suction wrapper presenting

device, means for transferring the tuck end of the wrapper to the bunch in the wrapping mechanism and hold it against the 20 bunch, a wrapper controlling device operating on the wrapper between the presenting device and the wrapping mechanism, and means for moving the controlling device lengthwise of the wrapping mechanism during the wrapping operation. 25

In testimony whereof, I have hereunto set my hand, in the presence of subscribing witnesses.
